CLAIM

The ornamental design for a pool cleaner, as shown and described.

DESCRIPTION

FIG. 1 is a front, left-side perspective view showing my new pool cleaner design;

FIG. 2 is a front elevation view thereof;

FIG. 3 is a top view thereof;

FIG. 4 is a right-side elevation view thereof;

FIG. 5 is a left-side elevation view thereof;

FIG. 6 is a rear elevation view thereof; and,

FIG. 7 is a bottom view thereof.

The broken lines shown in the figures are for the purpose of illustrating portions of the pool cleaner and form no part of the claimed design.

1 Claim, 7 Drawing Sheets(56)
